FIG. 1

FIG. 2

FIG. 3

FIG. 5

FIG. 4

FIG. 1 is a side elevation of a strapping tool for pressure sensitive tape or the like showing my new design;

FIG. 2 is a top plan view thereof;

FIG. 3 is a right end elevation thereof;

FIG. 4 is a perspective view thereof.

FIG. 5 is a fragmentary perspective view taken from the right of FIG. 3.

The side of the tool opposite to that shown in FIGURE 1 is plain except for rivet heads and nuts, as indicated by FIGURES 2 and 3.

I claim:

The ornamental design for a strapping tool for pressure sensitive tape or the like, as shown and described.
